UNITED STATES PATENT OFFICE

ABDIEL W. EICHELBERGER, OF HANOVER, PENNSYLVANIA.

RAILWAY CATTLE-GUARD.

SPECIFICATION forming part of Letters Patent No. 398,592, dated February 26, 1889.

Application filed June 12, 1888. Serial No. 276,816. (No model.)

To all whom it may concern:

Be it known that I, ABDIEL W. EICHELBERGER, of Hanover, in the county of York and State of Pennsylvania, have invented certain 5 Improvements in Railway Cattle-Guards, of which the following is a specification.

In the description of the said invention which follows reference is made to the accompanying drawings, forming a part hereof, 10 and in which—

Figure I is a plan or top view of a portion of a railway-track provided with my improved cattle-guard, and Fig. II an end view of Fig. I. Fig. III is a side view of Fig. I, looking in 15 the direction indicated by the arrow.

Similar letters of reference indicate similar parts in all the figures.

In the said drawings, A represents the rails of the track, and B the cross-ties.

20 C are the base-plates of the guard, secured in any suitable manner to the cross-ties. These base-plates are placed wherever it is desired to prevent cattle from crossing or straying on the track, and it will be seen that 25 they are at the sides as well as between the rails.

D are metallic toothed guard-bars, preferably of plate iron or steel, placed edgewise on the base-plates C, and held thereon by 30 means of brackets a. These brackets are

bolted, riveted, or otherwise secured to the sides of the guard-bars and to the base-plates C. Every other tooth of the guard-bars is bent to the right, and the intervening ones to the left. By this arrangement fewer guard-bars are required to give a desired space between them than if the teeth were in alignment with the portion of the bar beneath them, and the cost of the structure is therefore materially reduced. 35

At the ends of the cattle-guard the angle of the teeth is continued down to the base-plate, so as to lift anything hanging from the train which would be likely to become entangled with the bars, and, if desired, metallic strips F may be used, as shown, as an additional precaution. These strips are in an angular position, and may be backed with wood or not, as preferred. 40

I claim as my invention— 50
In a cattle-guard, the guard-bars having a toothed or serrated upper edge, the said teeth being set or arranged with each alternate tooth bent to one side, and the intervening teeth bent to the other side, substantially as 55 and for the purpose specified.

ABDIEL W. EICHELBERGER.
